HYDRAULIC CONTROL DEVICE

Jean Louis Gratzmuller, Paris, France

Application January 3, 1955, Serial No. 479,620

Claims priority, application France January 15, 1954

12 Claims. (Cl. 121—38)

The present invention relates to pressure fluid control systems whereby fluid under pressure is delivered in one direction for producing a desired effect and is discharged in another direction for exhaust or release.

In such control systems it is often desirable to reduce the time required for control valve operation and it is the main object of the present invention to provide an improved arrangement in which the desired time reduction for control valve operation is obtained in a simple but efficient manner.

It is a further object of the invention to provide a pushbutton operated fluid flow control device to be inserted in the pressure line of a fluid motor to permit flow of pressure fluid from a continuous fluid pressure source to one side of said motor while checking its return and to discharge fluid from said motor through said pressure line while checking the supply of pressure fluid from the source.

In carrying out the invention, two push button operated control valves are provided for controlling the main fluid flow control device, one of said pushbutton operated valves being adapted to control the flow of pressure fluid from the source to a valve actuating member of the main fluid flow control device responsive to fluid pressure from said source and also responsive to fluid pressure from said fluid motor, and the other pushbutton operated valve being adapted to connect said fluid pressure responsive valve actuating member of the main flow control device with the exhaust, the arrangement being such that a short manual or remote controlled opening of said one pushbutton operated control valve will subject the pressure responsive valve actuating member of the main flow control device to sufficient fluid pressure from the source to move said valve actuating member to a position in which said fluid motor is connected to the source, whereafter the fluid pressure conducted to the fluid motor through the main flow control device will maintain said pressure responsive valve actuating member in said position until the other pushbutton operated control valve has been opened to connect the pressure responsive valve actuating member to the exhaust to thereby permit the valve actuating member to return into a position in which it connects the fluid motor with the exhaust.

It is also an object of the invention to provide a pushbutton operated fluid flow control device particularly adapted for controlling the operation of electric circuit breakers having an operating piston one side of which is subjected to the force of resilient means and the other side of which may be subjected to fluid pressure adapted

2

to move the piston against the action of said resilient means.

Other objects and advantages of the invention will be apparent from the following detailed description together with the accompanying drawings, submitted for purposes of illustration only and not intended to define the scope of the invention, reference being had for that purpose to the subjoined claims.

In these drawings:

10 Figure 1 is a general diagrammatical view of a hydraulic control device according to the invention,

Figure 2 diagrammatically shows such a hydraulic control device in its application to the control of a spring-loaded jack,

15 Figure 3 shows the fluid flow control device as applied to the control of a single acting hydraulic jack adapted to operate an electric circuit breaker.

Referring to Figure 1, there is shown a hydraulic system adapted to deliver liquid under pressure in one direction for producing a desired effect, said system comprising a continuous liquid pressure source, e.g., a hydropneumatic accumulator 1, a utilization pressure line 2c leading to a fluid motor (not shown), and a low pressure tank or reservoir 43.

20 The flow control device according to the invention comprises a main flow control valve 9 having two movable valve members therein. The body of the main valve 9 is formed with two coaxial chambers, one of which constitutes a piston chamber and the other a valve chamber 53 provided with an inlet port connected to the source 1 by a pipe 2a, an outlet port communicating with the pressure line 2c, and an exhaust port connected to reservoir 43 by a pipe 44. In the example shown, the valve members of the main flow control valve 9 are constituted by two pistons 5 and 25 interconnected by a rod and slidably mounted in chamber 53 so as to selectively provide a passage between said inlet and outlet ports or a passage between said outlet and exhaust ports. The pistons 5 and 25 form parts of a differential piston assembly comprising also a larger pressure piston 8 slidably mounted in the piston chamber of valve 9 to divide said piston chamber into two compartments 46 and 47 of variable volume. The compartment 47 continuously communicates with the low-pressure container 43 through a duct 45. The compartment 46 may be communicated through pipes 48, 49, 50 with the source 1, under the control of a normally closed feeding valve 29, the opening of which is determined by triggering means diagrammatically shown in Figure 1, in the form of a push-button 6a. The compartment 46 may be also communicated through pipes 48, 51, 52 under the control of a normally closed unloading valve 24, e.g. with the low-pressure container 43, through a duct 54, not fully shown in Figure 1. The opening of the unloading valve 24 is determined by triggering means diagrammatically shown in Figure 1 under the shape of a push-button 15a.

Moreover, pipes 11, 51, 48 permanently communicate the utilization circuit 2c with the compartment 46 of the valve 9 and a flow-limiting device, diagrammatically shown in Figure 1 in the form of a calibrated hole 35 is interposed in the said pipe 11, for the hereunder described purpose.

This device operates as follows:

As soon as the push-button 6a is depressed; the feeding valve 29 is opened and the compartment 46 of the valve 9 is fed with pressure liquid from the source 1. Since the effective area of the piston 8 of the differential piston assembly is greater than the effective area of the valve member 5, both said areas being acted upon by the same liquid pressure, the differential piston assembly is shifted from the unloading position to the feeding position. The utilization circuit 2c leading to a hydraulic jack HJ is now fed with pressure liquid from the source 1, while piston 25 blocks communication between circuit 2c and the low-pressure container 43.

The pipe 11 conducts pressure liquid from the utilization circuit 2c, into the compartment 46 through the pipes 51 and 48, to thereby maintain, in the said compartment, a liquid pressure sufficiently high to maintain the valve member 5 in feeding position. From this moment, i.e. a short time after the feeding valve 29 has been actuated, this feeding valve may be closed again without causing interruption of the feeding of the utilization circuit. This condition persists until the push-button 15a is depressed, which causes opening of the unloading valve 24. The rate of the feeding flow of the compartment 46 from the utilization circuit 2c is limited by the calibrated hole 35 and it will be easily understood that if the relative calibrations of the said hole and the evacuation outlet controlled by the unloading valve 24 is so calculated that the rate of discharge through the said valve 24 is higher than the rate of feeding through the said calibrated hole, the liquid previously contained in the compartment 46 will be evacuated through the pipes 52, 54. In these conditions, the piston 8 being no more acted upon by any pressure, while the valve member 5 continues to be subjected to the pressure of the source 1 in the space 53, the differential piston assembly will be reset into unloading position, thus setting the utilization circuit 2c into communication with the container 43, while interrupting the feeding communication between the source 1 and the said utilization circuit 2c.

In the embodiment of Figure 2, there is shown at 1, as above, the source of pressure liquid and at 2a, 2b, 2c, 2d, the feeding duct of a hydraulic jack 3, e.g., provided to actuate a circuit-breaker, the following description being made with this assumption, it being well understood that the said jack 3 could control any other mechanism as well; 4 is the piston of said jack; 5 is a spring capable of returning the said piston into resting position when the jack is not under pressure. The derivation line provided for feeding the main flow control valve 9 from the utilization circuit (in this case, from the feeding duct 2c, 2d), is shown at 11a, 11b. In the embodiment shown in Fig. 2, the movable valve members 5 and 25 of main valve 9 are constituted by ball valves maintained in spaced relation by means of a rod 26. The valve actuating member of valve 9 is shown at 8, while 10 designates a spring loading said piston; 6 is a circuit-making electro-magnet and 15 is a circuit-breaking electro-magnet.

In this embodiment, the control device according to the invention ensures a rapid evacuation of the liquid from the circuit-making jack 3, in spite of the limited action of the electro-magnet 15 since it is possible to unload the circuit-making jack 3 through an outlet of a section as large as desired. Since, on the other hand, the ball valve 25 requires no lost motion before its opening, the device also ensures a short time of response to the circuit-breaking order. Rod 26 between the ball valves 5 and 25 ensures, when piston 8 is subjected to the liquid pressure from source 1 to close the ball valve 25, the opening of ball valve 5 while, conversely, when the piston 8 is unloaded, the spring 10 permits both opening of the ball valve 25 and closing of the ball valve 5. The feeding rate of flow through the delivery pipe 2a, 2b is preferably limited by means of a calibrated hole 27, to reduce the

leakage taking place during the very short time, when both valves 5 and 25 are simultaneously opened.

To the main flow control valve 9 are connected, as in Fig. 1, two independent feeding ducts; one of the said ducts 28a, 28b, 28c, controlled by a feeding valve 29 adapted to be triggered by the circuit-making electro-magnet 6, ensures the building-up of the initial pressure for closing the valve 25 and opening the valve 5; the other feeding duct 11a-11b, ensures automatic sustaining of the said pressure, as long as the piston 8 is not unloaded. In this embodiment, non-return valves 30, 31, the respective loading springs of which are shown at 32 and 33, are interposed between the feeding ducts 28b, 28c and 11a, 11b respectively, of the valve 9, to prevent liquid from counter-flowing towards either feeding source. The non-return valve 31 has for its purpose to avoid, as the feeding valve 29 is triggered, any loss of time in the building-up of the operative pressure below piston 8 while the non return valve 30 has the advantage of permitting to use a feeding valve 29, that may give rise to slight leakages towards the low-pressure container without prejudice. Moreover, the circuit-breaking electro-magnet 15 may be automatically controlled by a device 34 responsive to the pressure in the source 1, e.g., through a hydraulic system and electric circuits, not shown in Figure 2. Furthermore, the pressure-responsive device 34 may also control a device prohibiting any energizing of the circuit-making electro-magnet 6, when the pressure in the source 1 is insufficient for the purposes aimed at.

It will be easily understood that, if the piston 8 is to be rapidly unloaded, as the circuit breaking order is received, it is indispensable, that the feeding of the said piston through the ducts 11b, be reduced to a rate sufficiently small, with respect to the rate of discharge of the unloading valve 24, when the latter is opened by the electro-magnet 15.

For this purpose, as in Figure 1, a flow-limiter diagrammatically shown in the shape of a calibrated hole 35 is interposed on the duct 11.

Finally, in the embodiment of Figure 2, there is provided an evacuation outlet controlled by a valve 38 which is closed as valve 29 is opened, due to the interposition between both valves of a pushing rod 39. This arrangement has for its purpose to permit flowing to the liquid container 43 of leakages between the valve 29 and its seat, if any, such leakages risking, otherwise, to cause the unwanted building-up of liquid pressure below the piston 8 when ball valve 25 is in unloading position liquid flows through pipe 54' to container 43, and ducts 55, 56 provide communication between the chamber containing valve 38, the chamber containing valve 24 and pipe 54' respectively.

There is diagrammatically shown at 41 a second pressure-responsive device permitting the position of the jack 3, and hence, e.g., that of a circuit-breaker actuated thereby to be supervised by a mere reading of the pressure in the feeding duct 2c of the circuit-making jack 3.

This last arrangement is particularly advantageous in the case of the control of a circuit-breaker hydraulic jack.

Referring to Fig. 3, I have shown the control device as applied to an electric circuit breaker column comprising an upper tubular insulator D provided with two stationary contacts P1 and P2, a lower tubular insulator T, and a hydraulic jack Vp mounted between the insulators D and T and having its piston rod arranged to cooperate with the contacts P1 and P2 to make or break an electric circuit. The contacts P1 and P2 are connected into the circuit by the conductors C1 and C2, respectively. A spring Rp is mounted in the cylinder of jack Vp to urge the piston thereof in a direction to break the circuit and the insulator T is provided with a conduit K through which pressure liquid may be delivered to one side of said piston to move the latter against the action of spring Rp in a direction to make the circuit.

The construction of the control device shown in Fig. 3 is similar to that shown in Figs. 1 or 2 and the same reference numerals as in Figs. 1 or 2 have been applied to like parts. The main flow control valve 9 is connected to the continuous liquid pressure source 1 by pipe 2a, to the conduit K of insulator T by pipe 2d, and to the reservoir 43 by pipe 44 and the movable valve members 5 and 25 of the main flow control device 9 are adapted to selectively provide a passage for liquid flow from source 1 to one side of the operating piston of the circuit breaker, or a passage for liquid flow from said piston to reservoir 43.

Such a control system operates as follows:

When a circuit-making signal is received by the circuit-making electro-magnet 6, the said electro-magnet is energized and lifts the movable valve member 29 of the feeding valve from its seat to permit the flow of pressure liquid from source 1 into the space of the main valve 9 below the pressure responsive valve actuating piston 8 thereof. The latter, thus fed with pressure liquid, opens against the action of the spring 10 and the feeding valve 5 and closes the unloading valve 25. From this moment, the source 1 sends liquid under pressure into the circuit-making jack Vp through the conduits 2a, 2b, 2c, 2d and K to move the piston of jack Vp against the action of the return-spring Rp to set the circuit-breaker into the circuit-making position, as shown in Figure 3. The pressure in the space of main valve 9 below piston 8 is maintained through the duct 11 and its calibrated hole so that the valve member is in open position. In these conditions, the circuit-breaker is held in circuit-making position under the action of its jack Vp. This subsists as long as the piston 8 of the main valve 9 is not unloaded. The said unloading may be caused by the incoming into the circuit-breaking electro-magnet 15 of the circuit breaking signal. When thus energized, the said electro-magnet takes the valve member 24 of the unloading valve off its seat, so that piston 8 of the main valve is permitted to move under the action of its spring 10 in a direction to bring valve member 25 into open, and valve member 5 into closed position. The pressure line 2c, 2d and K is then unloaded and the circuit-breaker set into circuit-breaking position by its spring Rp, which is no more opposed by any liquid pressure.

The position of the circuit-breaker is displayed on the control station, by means of the selective action of a pressure responsive device M₁ on one of two visual indicators constituted, in the example shown, by a circuit-broken signal lamp Ld and by a circuit-made signal lamp Le. If the pressure of the source 1 is insufficient to ensure in the required conditions, the circuit-making stroke, an interlocking device, not shown, actuated, if desired, from the pressure responsive device M₂, prohibits any energizing of the circuit-making electro-magnet 15. Conversely, if the pressure of the source 1 becomes insufficient to maintain the circuit-breaker in circuit-making position, the said pressure responsive device M₂ automatically causes energizing of the circuit-breaking electro-magnet 15, and hence, the operation of the circuit-breaker into safe current interrupting position.

There is shown at Z a valve adapted to maintain in the duct through which the liquid is evacuated from the circuit-making jack Vp towards the liquid container 43, a level of liquid sufficiently high to provide the required length of insulation corresponding to the voltage of the current to be cut-off.

Finally, a pump P may be provided for feeding the source 1 from the liquid container 43.

It is clear therefore, that the invention provides a flow control device that is in combination with a pressure line, a tank and a continuous fluid pressure source. This flow control device is inserted between the source and the pressure line and comprises the main body 9.

This body is provided with a first port means such as X in each figure, first delivery conduit pipe portions such as 2a, 2b, between the source and the port X, Figures 2 and 3 and pipe portion 2a in Figure 1. The body 9 further has second port means such as Y, Figure 1, and the treble orifices Y', Y'', and Y''' in Figures 2 and 3. A second delivery conduit provides communication between the source 1 and this second port means. In Figure 1 this second delivery conduit is comprised by the pipe portion 50, the bore through the body containing valve 29, and pipe portions 49 and 48. In Figure 2 the second delivery conduit is pipe or duct portions 2a, 28a, the bore through the body containing valve 29, pipe portion 28b, past valve 30 and pipe portion 28c, into communication with the opening Y'. Each form of the invention further includes means establishing communication between the pressure line and the second port means. In Figure 1 the duct or pipe portion 11, pipe portion 51 and pipe portions 51 and 48 provide for flow of fluid from the pressure line back to the body beneath the piston 8. In Figure 2, this communication is established by pipe portion 11a, past valve 31 and pipe portion 11b terminating at opening Y''. The valve body further has a third port Z that is in communication with the pressure line and an exhaust port EP. Means such as pipe portion 2c in each figure establish communication between the third port and the pressure line, whereas pipe 44 in Figures 1 and 3 and pipe 54' in Figure 2 provide communication between the exhaust port EP and the tank 43. In addition, there is a communication established between the second port means and the tank. In Figure 1 this communication is by way of pipe portions 48 and 51 past valve 24 when open, through the bore 52 and pipe portion 54 back to tank. In Figure 2 the communication is established past valve 24 when open, past the opening Y''' and the further opening Y''', pipe portion 56, to the lower part of pipe 54' and thence to tank. A similar arrangement is incorporated in Figure 3. In the means that establishes the communication between the second port means and the pressure line is provided the permanent restricted passage constituted by the apertured element 35. Within the body are movable valve means 5, 25, which selectively provide a first passage between the first port means X and the third port Z and a second passage between the third port Z and the exhaust port EP. These valves are such that in the event of a pressure drop through the second port means, that is, a pressure drop beneath the piston 8, valve 5 will move to closed position, and valve 25 will open. For moving the valves in the reverse direction, namely, to the position shown in the drawings, the fluid pressure actuated member, the piston 8, is mounted in the body so that when fluid enters the body through the second port means, valve 5 is opened and valve 25 is closed. The second delivery conduit has therein a first control valve 29 controlling flow of fluid from the source 1 to the second port means Y, Fig. 1 and Y', Figures 2 and 3. A second control valve 24 is provided to connect the second port means with the tank. In Figure 1, when valve 24 is open, fluid will flow from beneath the piston 8 through conduit portion 51 past valve 24, ball 52 through pipe 54 to tank. When valve 24 is opened in Figures 2 and 3, fluid leaves the body through pipe 56, flows into pipe portion 44 (Fig. 3) and 54' (Fig. 2) thence to tank. Both of these valves are normally biased to closed position, either by the springs in Figure 1 or fluid pressure in the other two arrangements. Manually actuated operating means are provided to operate both of the valves. This last-mentioned means being either the push buttons 6a and 15a or the button controlled solenoids 6 and 15, in the other figures. As pointed out previously, with both of these control or triggering valves closed, pressure from the line flowing past the restriction 35 enters the body beneath the piston 8 and indefinitely maintains the valves 5 and 25 in the position in which it

has been previously brought, e.g. the position shown in Figures 2 and 3, wherein valve 5 is open and the first passage through the body between inlet port X and the third port Z is open, so that pressure is exerted continuously from source 1 on the pressure line. This condition exists until valve 24 is opened, which occasions the pressure drop beneath the piston 8, whereupon valve 5 will close and valve 25 will open, as previously explained.

What is claimed is:

1. In a hydraulic system for controlling a circuit-breaker, including a spring-loaded control jack operatively connected with said circuit-breaker to ensure one of the circuit-breaking and circuit-making strokes of the same, against the action of said spring, a source of pressure liquid, feeding duct means between said source and said control jack and a container at a pressure lower than that of said source, a hydraulic control device including a valve means in said feeding duct means between said source and said control jack and controlling communication between said control jack and said source and between said control jack and said container respectively, a loaded hydraulic pilot jack operatively connected with said valve means and including a piston adapted, when fed with liquid under pressure, to move said valve means against the load to establish communication between said source and said control jack, feeding means including a first normally closed triggering valve means operable when open to feed said pilot jack with liquid from source during a short time, unloading means including a second normally closed triggering valve means operable when open to permit exhaust of liquid from said pilot jack, liquid conducting means downstream of said control device for placing said pilot jack in permanent communication with said feeding duct means, for maintaining feeding of the pilot jack for an indefinite duration after the closing of said first triggering valve means so as to maintain the circuit breaker in one of its circuit-making and circuit breaking positions, and means for limiting the rate of flow through said liquid conducting means to maintain the rate of flow therethrough lower than the rate of discharge through said second triggering valve means, whereby said pilot jack means can be completely unloaded during the time of operation of said triggering valve means so as to reset said circuit breaker into the other one of said two positions.

2. In a hydraulic system as claimed in claim 1 and said hydraulic control device including a valve casing, said valve means comprising two valve members located within said casing, said valve members and said casing being constructed and arranged to establish the required communication with said feeding duct means without any lost motion as soon as said valve members are actuated, and an operative mechanical connection between said valve members and the piston of said pilot jack to selectively cause immediate opening of one of said valve members followed by closing of the other one as soon as said piston is actuated.

3. In a hydraulic system as claimed in claim 2 and each said valve member comprising a ball valve, said valve casing having a cylindrical passage therethrough communicating with said feeding duct means via said casing, a valve seat at each end of said passage for receiving said ball valves, said operative mechanical connection comprising a piston rod fast with the piston of said pilot jack and adapted to urge that ball valve that controls communication between said control jack and said container on its seat, and a rod slideable freely in said passage and interposed between said ball valves and having a length greater than the distance that would separate said ball valves if the same were simultaneously seated.

4. In a hydraulic system as claimed in claim 1 and said hydraulic device including a valve casing, said valve means comprising two valve elements, one of said valve

elements constituting a feeding valve element, said valve casing having a cylindrical passage, and a port providing communication between said passage and the feeding duct means downstream of the casing, through which fluid flows into said control jack, said feeding valve element comprising a ball cooperable with a seat provided at one end of said passage for controlling communication to said control jack, the other of said valve elements constituting an unloading valve element comprising the end of a rod fast with the piston of said pilot jack, and a second rod freely slideable in said passage interposed between said valve elements and fast with said first rod, said rods constituting the operative mechanical connection between said valve elements.

5. In a hydraulic system as claimed in claim 1 and a spring constituting the load on said pilot jack and continuously urging the piston of said jack and said valve means toward the unloading position of the latter.

6. In a hydraulic system as claimed in claim 1 and further including a non-return valve interposed in said feeding duct means between said source and said pilot jack.

7. In a hydraulic system as claimed in claim 1 and also including a non-return valve in said liquid conducting means between the means limiting the return of flow therethrough and said pilot jack.

8. In a hydraulic system as claimed in claim 1 and including a non-return valve interposed in said feeding duct means between said source and said pilot jack and another non-return valve interposed in said liquid conducting means between the means limiting the flow therethrough and said pilot jack.

9. In a hydraulic system as claimed in claim 1 and a push button operatively connected with at least one of said normally closed triggering valve means so as to permit opening thereof during a short time.

10. In a hydraulic system as claimed in claim 1 and an electro-magnet operatively associated with at least one of said normally closed triggering valve means and operable to open the same during a short time.

11. In a hydraulic control system as claimed in claim 1 and also including means operatively associated with said second triggering valve means and operable responsive to pressure in said source to actuate said second triggering valve means in response to a predetermined pressure in said source.

12. The combination with a pressure line, a tank and a continuous fluid pressure source for delivering fluid under pressure to said line, of a flow control device to be inserted between said source and said pressure line and comprising a body having a first port means, a first delivery conduit providing communication between said source and said first port means, said body further having second port means, a second delivery conduit providing communication between said source and said second port means, means establishing communication between said pressure line and said second port means, a third port communicating with said pressure line and an exhaust port; means establishing communication between said exhaust port and said tank, means establishing communication between said second port means and said tank, means providing a permanent restricted passage in the means establishing communication between said second port means and said pressure line, movable valve

means arranged in said body to selectively provide a first passage between said first port means and said third port and a second passage between said third port and said exhaust port, said valve means being mounted and arranged to normally close said first passage and to open said second passage in response to a pressure drop through said second port means, a fluid pressure responsive actuated member arranged in said body to move said valve means in the opposite direction in response to fluid pressure entering said body through said second port means to thereby close said second passage and

to open said first passage, a first control valve in said second delivery conduit for controlling the flow of fluid from said source to said second port means, a second control valve adapted to connect said second port means with said tank, said first and second control valves being normally biased to closed position, and manually actuated operating means adapted to operate each of said first and second control valves to open position, whereby with both said control valves closed pressure through said restricted passage indefinitely maintains said movable valve means in a position to provide a passage between said first port means and said third port to provide communication between said source and said pressure line

5
10

until operation of said second control valve means to open position.
